OIL-GAS BURNER

Frederick A. Loebel and Elroy M. Rulsey, Milwaukee, Wis., assignors to Cleaver-Brooks Company, a corporation of Wisconsin

Filed July 29, 1957, Ser. No. 674,874

4 Claims. (Cl. 158—11)

This invention relates to combustion apparatus adapted for burning either liquid or gaseous fuel, and has for a general object the provision of a new and improved apparatus of this type.

In combination oil and gas burning apparatus, a nozzle is provided adjacent the combustion zone for discharging oil in an atomized state to be burned in the combustion chamber, and additional means is provided for use alternatively to supply gaseous fuel for combustion in the same combustion chamber. Normally, the oil nozzle is positioned closely adjacent the combustion zone in order to properly discharge the oil for burning, and while the positioning of the nozzle in this manner is necessary and advantageously contributes to the provision of a combination oil and gas burning apparatus, it also gives rise to certain problems.

More specifically, one of the problems encountered is that excessive heat on the oil nozzle while burning gas may be sufficient to vaporize and coke any oil droplets left in the narrow nozzle passages, partially or totally blocking the passages. Thus, when burner operation is changed from gas firing to oil firing, oil atomization will be adversely affected because of the coke in the nozzle passages, and combustion will be poor. Further, it is possible, even if the oil nozzle is properly purged of oil, leaving only a thin film, that the heat on the oil film within the nozzle may bake the film so that it is difficult to take the nozzle apart for cleaning.

The problem is best solved by removing the nozzle from the hot zone, but it is essential that the changeover from gas firing to oil firing and vice versa, be as simple as possible with a minimum of manipulations required.

Accordingly, with the above and other considerations in mind, it is a more specific object of the invention to provide a new and improved combination oil and gas burner apparatus including means mounting the oil burner nozzle for movement from an advanced oil firing position closely adjacent to the combustion zone to a retracted, protected position to reduce the heat on the nozzle during gas firing.

Another object is to provide a new and improved combination oil and gas burner apparatus of the type described in the preceding paragraph including control means to prevent oil firing when the oil nozzle is in the retracted gas firing position.

Other objects and advantages will become readily apparent from the following detailed description taken in connection with the accompanying drawings, in which:

Fig. 1 is a fragmentary vertical sectional view taken along the longitudinal axis of a boiler structure embodying the principles of the present invention;

Fig. 2 is an enlarged fragmentary left end elevational view of the boiler structure illustrated in Fig. 1;

Fig. 3 is an enlarged fragmentary sectional view similar to Fig. 1, illustrating in detail the retractable oil nozzle mounting structure; and

Fig. 4 is an electric circuit diagram for use in the boiler structure illustrated.

While an illustrative embodiment of the invention is shown in the drawings and will be described in detail herein, the invention is susceptible of embodiment in many different forms, and it should be understood that the present disclosure is to be considered as an exemplification of the principles of the invention and is not intended to limit the invention to the embodiment illustrated. The scope of the invention will be pointed out in the appended claims.

10 Referring now to the drawings, as illustrated, the invention is embodied in a horizontal fire tube boiler which includes a horizontally disposed tubular boiler shell 10 which may be supported by any suitable means. Near the end of the boiler shell shown in Fig. 1, a tube sheet 11 extends across the shell and is suitably secured thereto as by welding illustrated at 12, and together with similar means provided at the end of the boiler shell not illustrated provides a means for supporting a fire tube 13. The fire tube 13 and additional smaller tubes 15 such as that illustrated at 14, with suitable additional structure, form multiple passes for combustion gases, through the boiler to an exhaust stack all as is conventional in boiler equipment of the type illustrated.

20 The fire tube 13 comprises a horizontally disposed, generally cylindrical tube of suitable metal material having an end fitted in an opening in the tube sheet 11 and welded to the sheet as illustrated at 15. The fire tube is lined with suitable refractory material as illustrated at 17 and 18, and insulating material as illustrated at 19, and the fire tube, together with the refractory materials form a combustion chamber in which combustion occurs during gas fired and oil fired operation of the boiler.

25 An annular body of insulating material 20 is positioned at the end of the fire tube as illustrated, and is supported by an annular casing 21 having a channel shaped across section and including an outwardly extending mounting flange 22. The flange 22 is fitted on a series of bolts 23 which are welded to an annular ring 24 in turn welded 30 inside the fire tube. The flange 22 abuts a sealing ring 25 and is secured in position by nuts 26.

35 At the front end of the boiler, the shell 10 is closed by an inner front boiler door 30 in the form of a circular plate which may be secured to a shell flange 31 by any suitable means such as bolts and nuts, or by a hinge mechanism, or by both means. In addition to the inner door 30, the front of the boiler shell is closed by an outer dish-shaped boiler door 33 of generally cylindrical configuration and including an outwardly turned flange 34 which abuts against the inner door 30 and which may be secured to the boiler shell in a suitable manner. The dish-shaped outer door and the inner door 30 define an air plenum chamber into which combustion air is drawn from atmosphere and from which the combustion air 40 flows to the combustion chamber to support burning during gas firing and oil firing of the boiler.

45 A cylindrical burner tube 36 is aligned with an opening 37 in the inner door 30 and with an opening 38 in the refractory 18. The burner tube defines a chamber 50 in which the oil nozzle 67 is mounted, and also forms an air duct through which combustion air flows from the plenum chamber to the combustion chamber. The burner tube is supported by an outwardly extending annular flange 39 welded to the tube and supported on the inner door 30 by machine screws 40. A sealing ring 41 is positioned between the flange 39 and the door 30 to prevent leakage of gases.

55 Combustion air is drawn into the plenum chamber through a suitable opening 44 provided in the outer door 33 by means of a blower which consists of a fan wheel 45 mounted on the drive shaft of a fan motor 46. The motor 46 may be supported in any suitable manner, but

preferably is conveniently mounted on the door 33. Air drawn into the plenum chamber by the fan passes to the burner tube 36 through a vaned diffuser or baffle 48 including a plurality of circumferentially spaced vanes 49 supported at opposite ends respectively by an outer annular plate 50 and an inner annular plate 51. The outer plate 50 is secured to the outer door 33, with an intervening sealing member 52, by machine screws 53, and the inner plate 51 is mounted on bolts 54 welded to the burner tube flange 39. Nuts 55 secure the plate 51 in place, and a sealing ring 56 is positioned between the rings 51 and 39.

The end of the burner tube 36 adjacent the combustion chamber is provided with an air diffuser including a cylindrical side wall 58 which is fitted in the burner tube and an end wall 59 which extends across the duct provided by the cylindrical wall 58 and the burner tube 36. The end wall 59 is provided with a central opening 60 and a plurality of circumferentially spaced, radially extending openings (not visible) with adjacent baffles or louvers 61 which function to direct air passing through the diffuser in a swirling pattern into the combustion chamber to provide the proper air flow pattern and a uniform distribution of combustion air in the combustion zone.

Gaseous fuel is supplied to the combustion chamber for gas firing of the burner through a gas conduit 63 which is positioned in outer spaced concentric relationship to the burner tube 36. The gas conduit is welded at one end to the burner tube flange 39, and is welded at the other end to the channel shaped casing 21. The conduit 63, with the burner tube 36 and the casing 21, forms an annular passage through which gas flows from a supply pipe 64 to the combustion chamber. At the end of the gas passage adjacent the combustion chamber, a ring 65 is secured inside the casing 21 as by welding, and forms a restriction in the gas passage which creates a slight pressure drop sufficient to cause an even distribution of the gas flowing from the annular gas passage to the combustion chamber. The gas supply pipe 64 leads from the conduit 63 through the boiler shell 10 for connection with a source of gaseous fuel, and is provided with a suitable flow controlling valve 66 of a conventional construction which is electrically controlled to open and close the gas conduit, preferably by a motorized operator.

Fuel oil is supplied to the combustion chamber for oil firing of the burner by means including a nozzle 67 which utilizes fuel oil supplied by an oil supply pipe 68 and air under pressure for atomizing the oil supplied by an air supply pipe 69 positioned in outer spaced concentric relationship to the oil pipe 68.

The air supply pipe 69 is threaded into nozzle body 70 and extends outwardly from the nozzle to a fitting 71 which in turn has a connection with a flexible conduit 72 adapted for connection with a source of atomizing air under pressure. If desired, an air pressure gauge 73 may be connected with the fitting 71.

At the discharge end, the oil supply pipe 68 opens into nozzle tip 75 and is supported therein. At the other end, the oil pipe is connected to a fitting 76 in turn connected to a supply conduit including a flexible portion 77 and a rigid portion 78. The rigid conduit portion 78 is adapted for connection with a suitable source of fuel oil, and is provided with a flow controlling valve 80 of a conventional type which is electrically controlled to open and close the oil conduit to control the flow of fuel oil to the nozzle, preferably by a solenoid means.

The oil nozzle 67 and the air and oil supply pipes 68 and 69 are supported in an elongated tubular support 82 which slidably receives the nozzle body 70 and a collar 83 on the air pipe 69 so that the nozzle is mounted for movement from an advanced oil burning position illustrated in full lines in Fig. 1 to a retracted position for gas firing illustrated in broken lines in Fig. 1.

The tubular support 82 is mounted at the end adjacent the combustion chamber by means of a spider-like structure including a central hub 85 on the tubular support, and spaced radial legs 86 extending outwardly from the hub 85 and having outer ends secured to the cylindrical wall 58 of the diffuser. At the opposite end, the tubular support is fitted in a collar 87 provided on a closure plate 88 which is mounted on bolts 89 extending from the diffuser plate 50.

The oil nozzle may be locked in either the advanced oil firing position or the retracted position for gas firing by means including a pivoted latch member 91 supported on a plate 92 having an integral collar 93 secured on the atomizing air pipe 69. The pivoted latch member is thereby mounted for movement with the nozzle and the air and oil pipes during advance or retraction of the latter, and is positioned to cooperate with a locking pin 95 suitably secured to the closure plate 88 and provided with a pair of spaced notches, such as that illustrated at 96, one for engagement by the hooklike end portion 91a of the latch member when the nozzle is in the advanced oil firing position and one for engagement by the latch member when the nozzle is in the retracted position.

In order to prevent the initiation of oil fired burner operation when the oil nozzle is in the retracted gas firing position, an interlocking control switch 98 is secured to the outside of the closure plate 88, and is provided with a switch actuating plunger 99 engageable by the plate 92 on the air pipe when the nozzle is in the advanced oil firing position to close the switch to permit oil fired burner operation. When the nozzle is in the retracted position for gas firing, the plate 92 frees the plunger 99 and the switch is opened to prevent oil fired burner operation, as will be explained in more detail presently in describing the electric circuit.

Gas fired and oil fired operation of the burner apparatus described may be initiated by a conventional electrically controlled ignition system generally designated 100 in the wiring diagram of Fig. 4 and, as seen in Fig. 1, including a gas fired pilot burner 101 and a suitable electric igniter 102. The gas burner 101 is in the form of an elongated conduit opening at one end adjacent the combustion chamber and connected at the opposite end, exteriorly of the mounting plate 88, to a suitable pilot gas supply line 103. The electric igniter 102 is encased for a portion of its length in suitable insulating means 104 and extends exteriorly of the mounting plate 88 for connection with suitable wiring 105. The gas conduit 103 may be connected with a supply of gaseous fuel and, as is conventional, may include a solenoid operated pilot valve (not shown) forming a part of the ignition system. The wiring 105 may be connected with a suitable source of electric power which conventionally includes an ignition transformer (not shown) forming a part of the ignition system.

In operation, the oil nozzle 67 is positioned in the advanced full line position of Fig. 1 for oil fired operation of the boiler, closely adjacent the combustion chamber, in order that the nozzle will properly discharge the atomized oil and air mixture into the combustion chamber to insure proper burning of the oil. When the boiler is operated on gaseous fuel supplied through the conduit 63, the heat of the combustion may be sufficient to cause coking or baking of the oil in the passages of the nozzle 67 if the nozzle is left in the advanced oil firing position. Accordingly, the construction described permits retraction of the nozzle in a direction away from the combustion chamber to the broken line position of Fig. 1 wherein the heat on the nozzle is sufficiently reduced to prevent the undesirable coking and baking referred to. Tests have been made, using thermocouples to ascertain the heat on the nozzle, which clearly indicate the temperature reductions at the nozzle at various retracted positions. The tabulation given below is a

sample of a test run on a 60 H.P. boiler with readings taken during low fire operation of the boiler (at approximately 20 H.P.) when the gas flame radiates the most heat back to the oil nozzle, and when the cooling air passing over the nozzle is at a minimum.

Retraction of oil nozzle from oil burning position, inches	Temperature at the nozzle tip in degrees Fahrenheit
0	330
1	323
2	320
3	300
4	245
5	215
6	185
8	185

From the tabulation above it will be seen that retraction of the nozzle at least 5 inches from the oil burning position places the nozzle in a relatively cool temperature zone of about 215° F., about 115° cooler than in the oil firing position, wherein coking and baking of the oil in the nozzle passages cannot occur. Other tests conducted on larger and smaller boilers show that in these also a 5 inch retraction of the nozzle is sufficient to prevent undesirable coking.

In addition to providing for retraction of the nozzle from the advanced oil firing position to the withdrawn gas firing position, the mounting means described above also permits removal of the nozzle and the supply pipes 68 and 69 completely from the tubular support 82 so that the nozzle is accessible exteriorly to permit maintenance and cleaning. If desired, the outer door 33 may be provided with a conveniently located bracket on which to hang the nozzle structure outside the plenum chamber without the need for disconnecting the flexible air supply conduit 72 or the flexible oil supply conduit 77 while cleaning.

As seen in the electric circuit diagram of Fig. 4, a gas-oil selector switch is provided to selectively obtain either gas fired or oil fired operation of the boiler. The selector switch includes two movable contacts 111 and 112, mechanically connected for joint operation under manual control. The movable contact 111 is adapted for closure with a stationary contact 113 in the position illustrated in Fig. 4 or to contact a stationary contact 114, while the movable contact 112 cooperates with a stationary contact 115 when positioned as illustrated or with a stationary contact 116.

As illustrated, the electric circuit includes, in addition to the elements already referred to, a switch means 117 which is representative of one or more automatically operable limit control switches responsive to upper or lower limits of operating conditions to either open or close the circuits automatically. Typical of such controls are water level, pressure, and temperature controls. Also, the circuit includes a switch means 118 which is representative of one or more manually operable control switches for controlling burner operation at the will of an operator, such as a manually operable burner switch for initiating boiler operation.

In operation, in order to obtain gas fired boiler operation with the limit control switch 117 and the operating control switch 118 closed, the gas-oil selector switch is moved from the position illustrated in Fig. 4 to a position in which the movable contact 111 engages the stationary contact 114 and the movable contact 112 engages the stationary contact 116. With the selector switch thus positioned, a circuit is completed from a suitable source of electric power through a wire 120, the control switches 117 and 118, the movable contact 111, the stationary contact 114, a wire 121, the movable contact 112, the stationary contact 116, a wire 122, the electric gas valve 66, and a wire 123 back to the source of power to energize the operating means for the gas valve

to open the valve, admitting gaseous fuel to combustion chamber. At the same time, a circuit is completed from the movable contact 111, through stationary contact 114, a wire 124, a wire 125, and the ignition 100 to energize the ignition system. Simultaneously, a circuit is completed from the wire 124 through a wire 126 and the motor 46 to energize this motor thereby driving the fan 45 to supply combustion air to the combustion chamber. The ignition system functions to admit gaseous fuel to 10 the pilot burner and to ignite such fuel, and the pilot burner in turn ignites the main supply of gaseous fuel. It will be seen that in obtaining gas fired burner operation in this fashion, the interlocking control switch 98 which is responsive to the position of the oil nozzle is 15 by-passed in energizing the gas valve, the ignition system and the blower motor, so that the condition of the interlocking control switch is of no consequence to this operation.

In order to obtain oil fired operation of the boiler, the 20 gas-oil selector switch is positioned as illustrated in Fig. 4, completing a circuit through the movable contact 111 and the stationary contact 113, a wire 127, the control switch 98, the wire 126 and motor 46 to energize the motor, driving the fan to supply combustion air to the combustion 25 chamber. At the same time, a circuit is completed through the wire 127, and the wire 125 to energize the ignition system 100. Also, a circuit is completed through the wire 125, the wire 124, the wire 121, the movable contact 112, the stationary contact 115, and a wire 128 to energize the electric oil valve 80, opening the oil supply conduit 77 to permit the flow of fuel oil to the burner nozzle. Thus, it will be seen that oil fired burner operation requires closure of the control switch 98, and thereby requires that the nozzle be positioned in the advanced oil burning position in order to obtain energization 35 of the motor 46, the ignition system 100 and the oil valve 80. Accordingly, oil fired burner operation cannot be initiated if the oil nozzle 67 is in the retracted gas firing position. This serves to prevent an attempted oil fired burner operation unless the oil nozzle is properly positioned for such operation.

It should be understood that the boiler operating control circuit illustrated in Fig. 4 is a simplified circuit for purposes of clarity in describing the interlocking control 45 switch 98, and in actual practice the circuit will include additional controls not illustrated such as the limit controls represented at 117, the operating controls represented at 118, starters or the like for the motor 46 and program controls in the ignition system which have not 50 been illustrated in detail.

We claim:

1. In a burner apparatus for alternatively burning liquid or gaseous fuel, means forming a combustion chamber open at one end for admitting fuel and air to support combustion, a burner nozzle positioned centrally in the open end of the combustion chamber for discharging liquid fuel in an atomized state into the combustion chamber, an air conduit disposed concentrically around the 55 burner nozzle for discharging combustion air into the open end of the combustion chamber, a gas conduit disposed concentrically around the air conduit for discharging gaseous fuel into the open end of the combustion chamber, means mounting the burner nozzle for movement between a first, advanced position adjacent the 60 open end of the combustion chamber for burning liquid and a second retracted position away from the open end of the combustion chamber during gas firing, a fan for delivering combustion air to the air conduit for gas firing and liquid firing, an electric motor for driving the fan, an electrically controlled liquid valve controlling the flow of liquid fuel to the burner nozzle, an electrically controlled gas valve controlling the flow of gaseous fuel to the gas conduit, electrically controlled ignition means for 65 initiating gas firing and liquid firing, circuit means in 70 75

cluding said motor, said valves, said ignition means and a selector switch selectively positionable alternatively energizing said liquid valve, said motor and said ignition means for liquid firing or said gas valve, said motor and said ignition means for gas firing, and switch means in said circuit means responsive to the position of the burner nozzle for preventing energization of the liquid valve, the motor and the ignition means when the selector switch is positioned for liquid firing and the burner nozzle is in the retracted gas firing position.

2. In a burner apparatus for burning either gas or oil, means forming a combustion chamber, a conduit positioned to discharge gaseous fuel into the combustion chamber for gas firing of the burner, an oil burner nozzle positioned adjacent the combustion chamber for discharging atomized fuel oil into the chamber for oil firing of the burner, means mounting the oil nozzle for movement from an advanced position adjacent the combustion chamber for oil firing to a retracted position spaced from the combustion chamber to reduce the heat on the nozzle during gas firing, an electrically energizable gas valve controlling the flow of gaseous fuel to the gas conduit, an electrically energizable oil valve controlling the flow of oil to the nozzle, an electric circuit including said motor and said valves, switch means in said circuit selectively positionable for alternatively energizing said gas valve and said ignition means for gas firing or said oil valve and said ignition means for oil firing, and a switch in said circuit responsive to the position of the burner nozzle for preventing energization of the oil valve and ignition means when the selectively positionable switch means is positioned for oil firing and the burner nozzle is in the retracted gas firing position.

3. In a burner apparatus for burning either gas or oil, means forming a combustion chamber, a conduit positioned to discharge gaseous fuel into the combustion chamber for gas firing of the burner, an oil burner nozzle positioned adjacent the combustion chamber for discharging atomized fuel oil into the chamber for oil firing of the burner, means mounting the oil nozzle for movement from an advanced position adjacent the combustion chamber for oil firing to a retracted position spaced from the combustion chamber to reduce the heat on the nozzle during gas firing, a fan for delivering combustion air to the combustion chamber for gas firing and oil firing, an electric motor for driving the fan, an electrically energizable gas

valve controlling the flow of gaseous fuel to the gas conduit, an electrically energizable oil valve controlling the flow of oil to the nozzle, an electric circuit including said motor and said valves, switch means in said circuit selectively positionable for alternatively energizing said gas valve and said motor for gas firing or for energizing said oil valve and said motor for oil firing, and a switch in said circuit responsive to the position of the burner nozzle for preventing energization of the oil valve and the motor when said selectively positionable switch means is positioned for oil firing and the burner nozzle is in the retracted gas firing position.

4. In a burner apparatus for burning either oil or gas, means forming a combustion chamber, a conduit positioned to discharge gaseous fuel into the combustion chamber for gas firing of the burner, an oil burner nozzle positioned in an opening to the combustion chamber for discharging atomized oil into the chamber for oil firing of the burner, a fuel oil supply conduit having one end connected to the oil nozzle for supplying oil thereto, means slidably supporting the oil nozzle and oil conduit for retraction from an advanced position wherein the nozzle is immediately adjacent the combustion chamber for oil firing to a second position wherein the nozzle is withdrawn and spaced from the combustion chamber during gas firing to reduce the heat on the nozzle and thereby reduce coking of oil in the nozzle, and means for locking the oil nozzle and oil conduit in either position, comprising, a latch member support mounted for movement with the oil conduit, a pivoted latch member on the latch member support, and a latch pin positioned alongside the path of the pivoted latch member when moved with the oil conduit, and having latching notches therein at spaced positions for engagement by the latch member respectively when the nozzle and conduit are in the advanced and retracted positions.
